DESIGN FOR A BOTTLE

Frasier Smith, Wheeling, W. Va., assignor to Hazel-Atlas Glass Company, Wheeling, W. Va., a corporation of West Virginia

Application August 23, 1934, Serial No. 53,031

Term of patent 14 years

To all whom it may concern:

Be it known that I, Frasier Smith, a citizen of the United States, residing at Wheeling, in the county of Ohio, and State of West Virginia, have invented a new, original, and ornamental Design for a Bottle, of which the following is a specification, reference being had to the accompanying drawing, forming part thereof.

The figure is a front elevational view of the bottle showing my new design. The opposite side of the bottle may be plain.

I claim:

The ornamental design for a bottle, as shown and described.

FRASIER SMITH.
